MEANS FOR CONDITIONING FRUITS AND
VEGETABLESWalker E. Simonson, Bartlesville, and Lon S.
Gregory, Tulsa, Okla., assignors to The Simo-
lene Company, Bartlesville, Okla.

Application April 30, 1934, Serial No. 723,138

2 Claims. (Cl. 99—271)

This invention relates to new and useful improvements in means for conditioning fruits and vegetables.

One object of the invention is to provide means for generating a gas suitable for the conditioning of fruits and vegetables which is an improvement of the means shown in the pending application of Walker E. Simonson, Serial No. 723,139, filed April 30, 1934.

10 An important object of the invention is to provide an improved machine having a gas generator wherein the gas production is constant.

Another object of the invention is to provide an improved machine for conditioning fruits and vegetables having a gas generator therein, and also having means for automatically maintaining the generator temperature within certain limits, whereby the proper pyrolysis of the gas is obtained.

20 A further object of the invention is to provide an improved generator for generating a gas suitable for conditioning fruits and vegetables from hydrocarbon mixtures or liquids, said liquids being stored above the generator whereby it will 25 flow by gravity and means for holding a constant pressure head above the generator, whereby said generator's gas production is constant.

A construction designed to carry out the invention will be hereinafter described, together with 30 other features of the invention.

The invention will be more readily understood from a reading of the following specification and by reference to the accompanying drawings, in which an example of the invention is shown, and 35 wherein:

Figure 1 is a front elevation of a conditioning machine constructed in accordance with the invention.

Figure 2 is a vertical sectional view of the same, 40 having the front wall removed.

Figure 3 is a transverse vertical sectional view, taken on the line 3—3 of Figure 1.

Figure 4 is a plan view.

Figure 5 is a horizontal cross-sectional view, 45 taken on the line 5—5 of Figure 3.

Figure 6 is a detail of the electrical furnace.

Figure 7 is a detail of the liquid gas valve control,

Figure 8 is a detail of the level chamber and 50 gascolator, and

Figure 9 is a diagrammatical view, showing the steam and gas system, together with a wiring diagram of the machine.

In the drawings the numeral 10 designates an 55 upright case or cabinet which is preferably square

in cross section, although this is not essential. The cabinet has its top open and a suitable grille 11 extends thereacross. The front wall of the cabinet terminates short of the lower end of said cabinet, thereby providing an opening 12 at the 5 lower end of said front wall. It is pointed out that the opening extends entirely across the width of the cabinet. The cabinet is provided with a false bottom 13 which is curved forwardly and downwardly and terminates at the lower end 10 of the opening 12, which is covered by a suitable grating 14. It is obvious that air entering the cabinet through the open top and passing downwardly through said cabinet is directed outwardly through the opening 12 by the curved bottom 15 13.

For controlling the temperature of the enclosure or room wherein the cabinet 10 may be, I provide a suitable heating unit within the cabinet. The unit includes a hanger bar 15 which is positioned within said cabinet and extends transversely thereof (Figures 2, 3 and 5). A plurality of metal heating strips 16 have their upper ends secured to the hanger bar 15. By observing Figure 2, it will be seen that the bars meet at their 20 upper ends, their lower ends being inclined outwardly toward the sides of the cabinet. The lower ends of said strips are secured to transverse supporting bars 17, similar to the hanger bar 15. It will be seen that due to the inclination and 25 position of the heating strips, air passing through the cabinet must pass through and around the strips. The strips are connected to each other by bus bars 18 and 19 (Figures 5 and 9). The bars are electrically connected to each other by 30 a short wire 18'. The bar 18 has a wire 18a leading therefrom and this wire has its other end connected to a thermostat 20 which is mounted on the front wall of the cabinet near the upper 35 end thereof. The thermostat has connection 30 through a wire 20a with a suitable source of electrical current. I have shown the wire 20a connected to a 220 volt three wire A. C. single phase source of supply. The electrical current to the thermostat is completed through a wire 40 19a which connects to one end of the bus bar 19. A suitable switch 21 which is mounted in a switch panel 22 on the front of the cabinet is connected in the wire 19a and controls the current passing 45 through the heating strips. 50

It is clear that when the switch 21 is closed the current will pass through the wire 19a to the bus bar 19, through said bar to the bar 18, and also through the strips 16, then through the wire 18a, the thermostat 20, and wire 20a to complete the 55

circuit. Thus so long as the switch is closed the strips are energized and serve to heat the air passing through the cabinet. The thermostat is set at a desired temperature and as soon as the temperature reaches this point, the circuit is broken by the thermostat cutting off the current to the strips. When the temperature falls below the desired point, the thermostat again closes the circuit and it is seen that the temperature of the air is automatically and at all times held constant.

For circulating the air in the enclosure wherein the cabinet is positioned, an electric fan 23 is mounted in a suitable bracket 24 in the top of the cabinet. The fan is connected in series with a triple pole double throw switch 25 which is mounted in the switch panel 22 on the front of the cabinet. The switch 25 is connected by wires 25a with a suitable source of supply which, as shown in the drawings, is a 220 volt three wire A. C. single phase. The fan carries a propeller type blade and due to the electrical hookup is reversible. When operated in a forward direction, it pulls the air in through the top and forces it downwardly through the cabinet 10 and then outwardly through the opening 12 in the front wall of said cabinet. When the fan is reversed, air is drawn upwardly through the cabinet and forced out the top of the same. It is pointed out that the fan provides a constant circulation of the air which the heating unit hereinbefore described holds at a constant temperature.

To properly condition fruits and vegetables, it has been found necessary to subject them to a gas which hastens their coloring and ripening. Different kinds of gas have been used with different results obtained. For generating a suitable gas for the conditioning of fruit and vegetables, we provide a gas generator or furnace 26 (Figures 3 and 6) which is mounted within the cabinet 10 between the metal heating strips 16. The generator includes a horizontal pipe 27 which extends entirely across the cabinet 10 and has its ends supported in the front and rear walls of the cabinet. The central portion of the pipe has an electrical coil 28 wound therearound and an insulating chamber 29 is provided around the coil and pipe. The chamber is formed by an enlarged cylindrical body 30 secured to circular end plates 31 which are supported on the pipe 27. Suitable insulating material 31, such as asbestos, is placed in the chamber and it is obvious that the heat from the coil 28 is utilized to heat the pipe 27.

The gas for conditioning the fruits and vegetables is produced by the pyrosynthesis of a hydrocarbon liquid in the electric generator or furnace 26. Pentane has been found to give very satisfactory results, but it is pointed out that other hydrocarbon liquids and hydrocarbon mixtures may be employed. Pentane is readily obtainable, easily handled and produces but little degenerate carbon during pyrosynthesis, so for purposes of description this hydrocarbon liquid will be used throughout the specification, although the invention is not to be limited to pentane.

The pentane is stored in a suitable tank or container 34' which is mounted on the rear of the cabinet 10 at the upper end thereof (Figures 3 and 9). The pentane flows by gravity into an outlet pipe 33' provided at the underside of the tank. A suitable filter screen 35' covers the outlet opening of the tank. The other end of the outlet pipe 33' connects to a level chamber 32' (Figure 8.) The chamber has a float 32' therein,

The float serves to open and close the outlet opening 33 in the lower end of the chamber 32. The opening 33 has a short pipe 34 leading to the interior of a gascolator 35. The gascolator operates similarly to the usual automobile gascolator and has a pipe 36 connecting said gascolator with the rear end of the pipe 27 of the generator 26. A shut-off valve 37, which is controlled by a lever 38 at one side of the cabinet 10, is connected in the pipe 36 and it is obvious that this valve controls the entrance of pentane to the generator. A check valve 39, which permits the pentane to pass downwardly but prevents its upward passage is connected in the pipe 36 below the control valve 37.

The pentane flows from the tank 34' into the level chamber 32. When sufficient liquid has entered this chamber the float 32' is raised and the pentane flows into the gascolator, from where it enters the pipe 36. With the valve 37 open, the pentane will enter the horizontal pipe 27 of the generator, where it will be heated. This heating of the pentane will form the gas used in the conditioning. The gas will escape from the pipe 27 through a vertical line 40 depending from the forward portion of said pipe (Figures 2 and 3). The line 40 is connected to the lower end of a gas purifier and cooler 41. This cooler and purifier which may be of any approved ordinary construction has a constant water level maintained therein in the usual way and the gas passes upwardly therethrough, where it is cooled and purified of any carbon or heavy tars. The gas is then discharged through a gas outlet pipe 42 which has its end projecting through the opening 12 in the front wall of the cabinet, and said gas mixes with the air being blown through the cabinet by the fan 23.

If the control valve 37 is adjusted to a definite position with a constant pressure head thereabove, the rate of flow of pentane will be constant and therefore the gas production will be constant. A constant head is obtained above said valve by the provision of the level chamber 32 and also by the provision of a vapor equalization line 44. The vapor equalization line includes pipes 45 and 46', which lead from the top of the level chamber 32 and the pipe 36 between the valves 37 and 39, to the top of the tank 34'. Thus it is obvious that when the valve 37 is opened and the apparatus is in operation the line 44 serves to equalize the back pressure at the level chamber, tank and pipe 36. This back pressure is further held constant by the constant water level in the gas cooler and purifier 41. That is to say, by the maintenance of a predetermined body of water constantly in the cooler and purifier 41 the flow of the gas is controlled and maintained with substantial regularity and without appreciable fluctuation, whereby, with the adjustment of the pentane supply control valve 37, as hereinabove described, a definite and steady generation of gas is accomplished and the flow of the pentane from the supply tank 34' to the level chamber 32 and from said chamber 32, through the gascolater 35, to the check valve 39 is constant, because, by the provision of the pressure equalization line 44, 45 and 46. Said equalization line is manifestly effective whether or not there is sufficient back pressure created in the gas generator pipe 27 to hold the check valve 39 closed, and such condition may momentarily occur from time to time during the operation of the apparatus. Even should any gas pressure back up through 75

the check valve 39, the pressure equalizing effect in the tank 34' and level chamber 32 is still accomplished by the arrangement of the pipes 44, 45 and 46. The level chamber 32 operates similarly to the float chamber of an automobile carburetor, and maintains a constant level of pentane in said chamber. Thus it is possible to set the liquid valve lever 38 with a stop 38' and after calibration ascertain the amount of gas produced per unit of time. Since the cubic content of the room may be measured and the rate of gas produced is known, it is possible to determine the length of time the generator 26 must operate to give the desired gas concentration for a particular fruit or vegetable.

To obtain the proper pyrolysis of the gas, it is necessary that the generator or furnace temperature be maintained between definite limits. For automatically controlling the temperature of the generator, we provide a generator thermostat 46. This thermostat includes a horizontal iron tube 47 which is suitably supported in and secured to a bearing 48 which is screwed into the rear end of the pipe 27 of the generator 26. By observing Figure 6, it will be seen that the tube 47 extends longitudinally within the pipe 27. A copper rod 49 is positioned within the tube and has its inner end rigidly secured to the inner end of the tube. The other end of the rod extends outwardly from the outer end of the tube and is alined to engage an electrical contact 50 carried by suitable supports 51 extending from the bearing 48. When the tube 47 and rod 49 are heated, the heat will cause expansion of the same. The rod, being of copper will expand more rapidly than the tube which is of iron, and the engagement of the copper rod with the contact 50 will close an electrical circuit, as will be hereinafter explained.

The electrical hookup of the coil 28 of the generator 26 and its controlling thermostat is clearly shown in Figure 9. One end of the coil 28 is connected by a lead wire 28a through the thermostat 20 to one side of the 220 volt three wire single phase A. C. source. A switch 52 is connected in the wire 28a and this switch is mounted in the panel 22 on the front wall of the cabinet 10. The other end of the coil is connected by a lead wire 28b to the source of supply. A relay operated switch 53 is connected in this wire. Thus, it is obvious that the current passing through the coil 28 is controlled by the manually operated switch 52 and the relay operated switch 53, and the thermostat 20.

The contact 50 of the generator thermostat 46 has a wire 50a leading therefrom to one side of a transformer 54. The transformer is supplied with electricity from the 220 volt three wire single phase A. C. source. The opposite side of the transformer has a wire 54a leading therefrom and the other end of this wire is connected to the bearing 48 in which the tube 47 and copper rod 49 are secured. A relay 55 which operates the switch 53 when energized is connected in the wire 54a. It will be seen that when the coil 28 of the generator heats the copper rod 49, said rod will expand to engage the contact 50. This will close the circuit to the transformer 54 through the wires 50a and 54a to energize the relay 55. When the relay is energized, the switch 53 will be operated to break the circuit to the heating coil 28, thereby shutting off the heat in the generator. A suitable pilot lamp 56 is connected by wires 56a and 56b to the wire 54a, and said pilot lamp is lighted each

time the relay is operated, thereby showing when the generator has reached its maximum heat. When the rod 49 cools sufficiently to break the circuit through the transformer, the relay 55 is de-energized and the switch 53 returns to its normal position, again closing the circuit to permit the coil 28 to heat. Thus, the heat of the generator is automatically controlled. Of course, by manually operating the switch 52, the control of the generator by the operator is had.

Some fruits and vegetables require that sufficient humidity of the air in the enclosure or room be maintained. If the humidity is too low, the material under treatment will show a distinct loss in weight and the skins will become shrivelled and broken. To control the humidity of the air in the room, we mix steam with the air which is passing through the cabinet 10. In providing steam, we utilize the generator 26.

A water tank 56' is positioned on the rear wall 20 of the cabinet 10 adjacent the pentane tank 34'. If desired, and as we have shown in the drawings, the two tanks may be a single tank with a partition therein. The water tank has a vertical outlet pipe 57 leading downwardly therefrom. This pipe is provided with a water orifice 57' which controls the flow of the water from the tank 56' through the pipe. A suitable check valve 58' is also connected in this pipe. The lower end of the vertical pipe 57 connects 30 to a horizontal pipe 58 which has its inner end connected to the pentane lead pipe 36, below the check valve 39. A cut-off valve 59 is positioned in the pipe 58 and controls the entrance of the water into the lead pipe 36. The outer 35 end of the pipe 58 has a steam outlet pipe 60 secured thereto. This pipe 60 extends vertically and has its upper end open.

The water draining downwardly by gravity from the tank 56', flows downwardly through the pipe 57 into the pipe 58 and then into the pentane lead pipe 36. It is pointed out that the flow of pentane is cut off at this time, the valve 37 being closed. The water then flows into the generator 26 where it is heated and steam formed. The 40 steam then rises through the pipe 36, into the pipe 58, and finally out into the atmosphere through the pipe 60. The steam cannot go upwardly in the pipe 36 into the pentane tank or upwardly in the pipe 57, being prevented by the 45 check valves 39 and 58', respectively. The water within the generator which is not converted into steam will drain downwardly from the generator into the gas purifier and cooler 41, thereby maintaining a constant supply of water in said 50 cooler and purifier. It is pointed out that the generator is utilized to generate both steam and gas, but it can handle only one at a time.

In operation the fruit or vegetable to be conditioned or treated is placed in an air-tight room 60 or enclosure. The cabinet 10 is set within the room and the fan 23 is turned on to draw air in through the top of the cabinet and force it through and around the metal heating strips 16 and out of the opening 12 at the lower front 65 wall of said cabinet. This sets up a circulation of air within the room. The thermostat 20 is then set at the desired temperature and the switch 21 is turned to its "on" position. This closes the electrical circuit to the heating strips 70 16 and the room is then heated to the desired temperature. During this time the fan is operating to circulate the hot air.

If it is desirable, depending on the particular fruit or vegetable, to raise the humidity of the 75

air in the room, the switch 52 which controls the generator coil 28 is closed. The water control valve 58 is then opened and water flows into the generator 26. The steam formed therein escapes from the upper end of the pipe 68 and the emitting steam is drawn through the cabinet by the draft of air at the top of the machine, and is mixed with the air and discharged into the room. The water control valve 58 is left open until the desired saturation is reached, which may be ascertained by a hygrometer (not shown) and the valve is then closed.

To release the gas into the room, it is only necessary to open the control valve 38 in the pipe 36, the switch 52 to the generator coil being closed. The pentane will enter the generator and be heated. The gas thus formed will be discharged through the gas outlet pipe 42 into the room. The length of time that the gas is being discharged depends entirely on the particular fruit or vegetable which is being treated. For instance, bananas are treated under different conditions than celery or citrus fruits. Each fruit or vegetable, however, must have a certain constant temperature and humidity and must be subjected to a certain gas concentration to be properly treated and conditioned.

The device herein described has a positive control of these conditions, as well as a means for circulating the air and gas within the room. After a particular fruit or vegetable has been treated, the fan 23 can be reversed and a duct (not shown) placed over the upper end of the cabinet to draw the gas from the room. Heretofore it has been the practice to release gas into the room from pressure containers which are entirely separate from the heating means. The generator 26 is an important feature of the invention in that it is possible to get the desired and necessary gas concentration. We have described pentane as used but it is again brought out that any hydrocarbon liquid or mixture, such as hexane, can be used if the proper conditions for their pyrolysis are maintained.

The description which has been given recites more or less detail of a particular embodiment of the invention, which is set forth as new and useful; however, we desire it understood that the invention is not limited to such exact details of construction, because it is manifest that changes and modifications may be made, within the scope of the appended claims, without departing from the spirit of the invention.

What we claim and desire to secure by Letters Patent, is:

1. In a self-contained apparatus for conditioning fruits and vegetables located within an enclosure, the combination of a portable cabinet having an air passage therethrough, electrical heating means within the passage for heating the air passing therethrough, an electrically operated steam and gas generator within said air passage and in proximity to the heating means thereof, 10 said generator comprising a casing having insulating material therein and a tubular central generating member surrounded by an electrical heating coil, means for manually and automatically controlling the operation of said heater and 15 generator, including a thermostat exposed to the atmosphere externally of the cabinet, a water container on said cabinet, a separate gas producing liquid container on said cabinet, and manually regulatable means for supplying the water or 20 gas producing liquid separately to said central generating member of the generator, and means for delivering the generated steam or gas to the air stream leaving the passageway in said cabinet.

2. In an apparatus for conditioning fruits and 25 vegetables, as herein described, a portable cabinet having an air passage therethrough, an electrical heating element within the cabinet for heating the air passing through said passage, and an electrically heated steam and gas generator in 30 said cabinet comprising, a cylindrical casing located within the air passage, a central tubular member within said cylindrical casing, an electrical heating coil surrounding said tubular member within said cylindrical casing, separate 35 sources of supply of water and gas producing liquid to said generator, manually operable means for effecting the supply of water or gas producing liquid separately and selectively to said generator, at will, means for delivering the product generated in said generator to the air stream leaving said air passage of the cabinet, and means for automatically controlling the temperature of 40 said heating element and said generator including a thermostat exposed to the atmosphere externally 45 of the cabinet and additional control means for the generator including a relay operated switch in the generator circuit and a thermal element in the generator for actuating the switch operating relay to open the circuit. 50
